USPC D7/391, 392, 392.1, 396.1, 396.2, 509,
 D7/510, 511, 514, 518; D9/435, 436,
 D9/440, 447, 451, 516, 530, 738

The ornamental design for a drinking cup lid, as shown and described.

CPC B65D 47/122
 See application file for complete search history.

References Cited**DESCRIPTION****U.S. PATENT DOCUMENTS**

FIG. 1 is a front top-right perspective view of a drinking cup lid, showing my new design;

FIG. 2 is a rear top-left perspective view thereof;

FIG. 3 is a front elevation view thereof;

FIG. 4 is a right side elevation view thereof;

FIG. 5 is a rear elevation view thereof;

FIG. 6 is a top view thereof; and,

FIG. 7 is a left side elevation view thereof.

The portions of the drawings depicted in broken lines are included for environmental purposes only, and form no part of the claimed invention.
